UNITED STATES PATENT OFFICE.

WILLIAM P. CRARY, OF NEW YORK, N. Y.

BOTTLE-STOPPER.

SPECIFICATION forming part of Letters Patent No. 398,944, dated March 5, 1889.

Application filed August 29, 1888. Serial No. 284,052. (No model.)

To all whom it may concern:

Be it known that I, WILLIAM P. CRARY, of the city, county, and State of New York, have invented a new and Improved Bottle-Stopper, of which the following is a full, clear, and exact description.

The object of my invention is to provide bottle-stoppers of cork or other material with means whereby they may be easily withdrawn from a bottle without the use of a corkscrew; and to this end my invention consists in combining with the cork a covering of cloth, animal tissue, or other material, which is tied above the top of the cork and extends above the binding-cord, to furnish a grasp or handle for withdrawing the cork from the bottle, and when made of sufficient extent adapted to be tied down over the neck of the bottle to protect the cork and neck, or as a cap.

Reference is to be had to the accompanying drawings, forming a part of this specification, in which similar letters of reference indicate corresponding parts in all the figures.

Figure 1 shows my invention applied to a bottle, the cork-covering being shown tied down over the neck of the bottle. Fig. 2 is a sectional elevation showing the cork in the bottle and the covering elevated ready to be grasped for withdrawing the stopper. Figs. 3, 4, and 5 show stoppers of various sizes constructed in accordance with my invention.

To a common stopper, A, of cork or othersuit-

able material, I apply a covering, B, of cloth, skin, rubber tissue—that is, raw india-rubber rolled into sheets—or other suitable material. 35 This covering is gathered over the top of the stopper and tightly secured by a wire or cord, C. The folded portion of the fabric above the stopper forms a handle, which may be conveniently grasped and the cork readily withdrawn from the bottle without a corkscrew and without injury to the cork. In some cases the handle portion D of the fabric will be made quite short, as in Figs. 3 and 4, while in others it will be made of considerable 45 length, as in Figs. 1, 2, and 4, adapting it to be folded down over the neck of the bottle E and tied by a cord or wire, F, thus forming a perfect covering for the cork and neck—in other words, a cap. 50

Having thus described my invention, what I claim as new, and desire to secure by Letters Patent, is—

As an improved article of manufacture, a stopper comprising a cork, A, and a covering, B, of fabric, animal or rubber tissue, secured by cord C above the cork and extended to form the handle or grasp D for withdrawing the cork, substantially as described. 55

WILLIAM P. CRARY.
